UNITED STATES PATENT OFFICE

2,580,574

APPARATUS FOR CONTINUOUSLY MARKING METAL OBJECTS

William S. Miller, Youngstown, Ohio, assignor of fifty per cent to George Lubic, Youngstown, Ohio

Application March 28, 1949, Serial No. 83,864

2 Claims.

(Cl. 101—5)

1

This invention relates to marking devices and more particularly to a device for continuously marking metal objects such as pipe strip and the like as it is produced.

The principal object of the invention is the provision of apparatus for continuously marking metal objects.

A further object of the invention is the provision of a device having removable and replaceable marking elements.

A still further object of the invention is the provision of apparatus for continuously marking metal objects and incorporating adjustable tensioning means.

A still further object of the invention is the provision of apparatus for continuously marking metal objects and incorporating readily removable rotatable marking element assemblies.

The apparatus for continuously marking metal objects disclosed herein has been designed to provide a simple, economic and efficient means of continuously applying identifying indicia to metal objects such as pipe strip and the like as the same are produced in the mill. It is well known that it is desirable to identify metal articles and particularly pipe continuously along the length thereof so that the pipe, after having been placed in use, may always be identified as to the producer, the order number, date of production, etc. In the past such information has been stenciled upon the lengths of pipe after they have been completed which is a slow expensive process and frequently omitted with the result that the pipe is shipped and used with no identifying marking thereon.

The present invention avoids such objectionable practice as it enables the pipe to be continuously marked as it is formed and the marking device itself may be readily changed to provide different marking elements whenever desired.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a front view with parts broken away and parts in cross section of the apparatus for continuously marking metal objects.

2

Figure 2 is a side view with parts broken away and parts in cross section of the apparatus for continuously marking metal objects.

By referring to the drawings and Figure 1 in particular it will be seen that a portion of a mounting bracket 10 is illustrated and secured to a tubular body member 11 which is positioned vertically over the path of the metal object to be marked, such as a pipe 12. The tubular body member 11 has a guide member 13 positioned therein, the upper end of which is provided with a thread pattern 14 and engaged in a nut 15 which in turn rests on the upper end of the tubular body member 11. The lower end of the guide member 13 extends downwardly and out of the tubular body member 11 and the guide member 13, which is tubular, encloses a T headed bolt 16, the upper end of which is provided with a thread pattern 17 which engages a nut 18 which in turn rests upon the upper end of the guide member 13 hereinafter referred to.

A clevis 19 is positioned over the T headed bolt 16 and a coil spring 20 is positioned between the upper surface of the clevis 19 and the lower surface of the tubular body member 11. The guide member 13 is provided with a plurality of threaded openings 21 and the bottom of the tubular body member 11 is notched as at 22 so that an adjusting bolt 23 may be positioned in one of the openings 21 and the body member 11 in turn positioned thereon. The arms of the clevis 19 have oppositely disposed openings 24—24 therein and carry a removable shaft 25 which in turn has a composite marking wheel secured thereto.

The composite marking wheel includes a pair of disc-like members 26 and 27, the disc-like member 26 having an annular channel 28 formed therein and an annular rib 29 formed thereon and in the area of the channel 28. A plurality of marking elements 30, each of which has a suitable letter or number forming a raised portion thereof and extending beyond the periphery of the disc-like members 26 and 27, are clamped between the discs 26 and 27 in the annular channel 28 and with cut out areas in their sides registering with the annular rib 29. The disc 26 is provided with a plurality of radially spaced drilled and tapped openings 31 and the disc 27 is provided with a matching plurality of drilled openings 32 for the reception of a plurality of bolts 33 which hold the marking wheel assembly together. It will thus be seen that when a metal object such as the pipe 12 is emerging from its forming apparatus and is heated so that the marking elements 30 may impress their several characters thereinto, the device may be positioned in proper en-

gagement with the pipe 12 by adjusting the guide 13 and the T headed bolt 16 vertically by means of the adjustment nuts 15 and 18, respectively. For various sizes of pipes, further adjustment may be made to the vertical height of the assembled apparatus by shifting the adjustment bolt 23 with respect to the several threaded openings 21 in the guide 13.

It will be obvious to those skilled in the art that the marking wheel assembly comprising the discs 26 and 27 and the marking elements 30 are always engaged upon the metal object 12 with proper tension due to the provision of the coil spring 20 and the unusual adjustability of the several parts of the device with respect to one another.

In Figure 2 of the drawings a side elevation of the apparatus is disclosed and by referring thereto it will be observed that the pipe 12 moves from one side to the other beneath the marking wheel assembly of the discs 26 and 27 and that each of the marking elements 30 is tapered so that they may be positioned in registry between the discs 26 and 27 to complete the marking wheel assembly, as shown.

It will be obvious that when it is desired to change the marking, the tension may be relieved on the device and the shaft 25 temporarily removed to permit a new marking wheel assembly to be positioned in the device.

It will thus be seen that the several objects of the invention are met by the construction disclosed herein and that a simple, efficient and easily changeable marking device has been disclosed which is particularly adaptable for marking desirable indicia on metal articles.

Having thus described my invention, what I claim is:

1. Apparatus for continuously marking metal objects comprising a tubular support member, a tubular guide member movably positioned in said tubular support member, a T headed bolt movably positioned in said tubular guide member and

means adjustably securing said tubular guide member to said tubular support member, a clevis positioned on the said T headed bolt, and tensioning means disposed between the said tubular support member and the said clevis, a marking wheel carried by said clevis for rotatable engagement with an article to be marked.

2. Apparatus for continuously marking metal objects comprising a tubular support member, a tubular guide member movably positioned in said tubular support member, a T headed bolt movably positioned in said tubular guide member and means adjustably securing said tubular guide member to said tubular support member, a clevis positioned on the said T headed bolt and tensioning means disposed between the said tubular support member and the said clevis, means adjustably positioning the said tubular guide in the said tubular support and means adjustably positioning the said T headed bolt in the said tubular guide, a marking wheel carried by said clevis for rotatable engagement with an article to be marked.

WILLIAM S. MILLER.
